Application March 18, 1937, Serial No. 131,575

2 Claims. (Cl. 261—49)

This invention relates to an improved and automatically controlled air valve type of carburetor for internal combustion engines.

It is an important object of this invention to provide an improved air valve type of carburetor wherein the mixture ratio is varied between that most suitable for maximum economy at different throttle settings and that developing the most power, the change over in either direction being automatically accomplished by means responsive to whether the air valve opens more or less than that opening normally corresponding to the existing throttle opening. It will be evident that if the air valve does not open to a point corresponding to the throttle setting, then the engine is laboring or working under full power as its speed of rotation is not sufficient to demand enough air to open the air valve to the required extent. Under such circumstances, a richer or powerful mixture is called for to enable the engine to develop its maximum power at the given throttle opening, even if such opening is only partial. Contrawise, when the engine speed exceeds that normal to a given throttle opening, the increased speed will cause an increased opening of the air valve, under which circumstances an ultra lean mixture is automatically provided by the carburetor of this invention, thus economizing on fuel, reducing the overspeeding effect and serving to scavenge the cylinders and reduce the carbon therein, without damage to the engine because under these circumstances the load is lighter.

It is a further object of this invention to provide an improved air valve carburetor wherein the fuel metering is under the coordinated control of both the air valve and the throttle, either of which can automatically dominate the metering control to provide either an economy or power mixture ratio.

It is also an object of this invention to provide an air valve type of carburetor, wherein cams operated separately by the air valve and throttle coact with a fuel metering pin control, the arrangement being such that the action of each cam on the metering control is subject to adjustment over the entire range, and the heels and toes of each cam are separately adjustable to vary the mixture control at the extremes without affecting the conditions of normal operation at part loads.

It is another object of this invention to provide an improved air valve carburetor wherein better starting conditions due to improved atomization of the fuel under starting conditions is

obtained when using only the main fuel jet, thus eliminating the need of an idling nozzle or bypass and the consequent irregularity found in the change-over to normal operating conditions.

It is a further object of this invention to provide an improved and simplified accelerating pump and dash-pot arranged to supply accelerating fuel during the first portion of the opening movement of the air valve, and only when the air valve opens rapidly in response to engine suction.

It is still another object of this invention to provide an improved and simplified choke control for enrichening the mixture for starting purposes, the choke control being arranged to cooperate with both the air valve and the fuel metering control to progressively increase the spring load on the air valve, and to increase the fuel supply, as well as being so coordinated with the air valve that a rapid opening thereof will release the choke control.

Other and further objects of this invention will become apparent from the following disclosures, taken in connection with the accompanying drawings, in which:

Figure 1 is a top plan view of a carburetor embodying the features of this invention;

Figure 2 is an elevation of the throttle lever or front side of the carburetor;

Figure 3 is an elevation of the throttle cam or rear side of the carburetor;

Figure 4 is a front central vertical section of the carburetor, with parts shown in elevation, corresponding to the section line IV—IV of Figure 1;

Figure 5 is a section on the line V—V of Figure 4, showing the fuel bowl and float mechanism;

Figure 6 is a section on the line VI—VI of Figure 2, showing the accelerator pump and dash pot construction;

Figure 7 is a fragmentary detail section taken along the line VII—VII of Figure 1, showing the choke or mixture enrichening control; and

Figure 8 is a distorted diagrammatic outline layout of the cooperating air valve and throttle linkages controlling the fuel metering pin.

As shown on the drawings:

The improved air valve type of carburetor of this invention has been shown as of the down-draft type in the accompanying drawings, although it will be evident that the invention is not limited to the illustrated form. The carburetor, as illustrated, comprises three members through which the mixture passage continues. The uppermost member or casing 11 has an ex-

ternal seat 12 to receive an air cleaner and is internally profiled at 13 to cooperate with an air valve 14. It also provides bearings for a cross-shaft 15 carrying a power cam 16 at one end.

The center member 17 provides a continuation 18 of the mixture passage and has a projecting portion 19 which serves as a fuel chamber cover, the cover also providing a bearing for a metering 10 control shaft 20. The air valve 14 is slidably mounted on a vertical guide 21 mounted in a bridge 22 across the mixture passage 18.

The lower member 23 contains a Venturi passage 24 forming a continuation of the mixture 15 passage 18, a throttle shaft 25 being located in the lower portion of the Venturi passage adjacent a carburetor mounting flange 26. The lower member 22 also embodies a fuel chamber 27 and an accelerating pump and dash pot chamber 28.

20 The fuel chamber 27 contains a float 29 which actuates a fuel admission valve 30 controlling the entry of fuel from a source of supply 31.

The fuel chamber 27 extends partly around the barrel of the lower member 23 in order to 25 provide more reserve fuel and to place a fuel outlet passage 32 approximately centrally of the fuel volume, in order to maintain the normal fuel level at the passage 32, in spite of unusual 30 inclinations of the carburetor as a whole. The passage 32 comprises a tube depending from the center member and communicating with a passage 33 in the bridge 22, from which a fuel spray nozzle 34 extends downwardly (in the case of a down draft carburetor) into the restricted zone of 35 the Venturi passage 24. The fuel chamber also communicates through a passage 35 with the bottom of the dash pot and accelerator pump chamber 28, a ball check valve 36 being provided at the bottom of the chamber 28 to prevent 40 return flow of fuel.

The air valve 14 is slidably mounted on a guide 21 forming an extension of the fuel nozzle, the guide being passaged at 37 to receive an air valve spring 38, the calibration of this spring in 45 relation to the profile of the passage 13 about the air valve being such that as the air valve opens, the mixture tends to be progressively leaned by the control mechanism to be hereinafter mentioned. In other words, the spring 50 is purposely made lighter than would be required to maintain a uniform fuel and air ratio as the valve 14 opens. It will be evident in this connection that the chosen spring rate or strength determines the depression range within the carburetor in response to engine suction, and the 55 length of the spring controls the initial depression required to open the air valve.

Control of the fuel supply to the nozzle 34 centers about a metering pin 39 cooperating with 60 a tapered section 40 in the horizontal fuel passage 33. The pin 39 is of cylindrical section with an external head 41 backed by a light spring 42 which retracts the pin, the controlled proximity of the pin to the tapered section 40 metering 65 the flow of fuel to the nozzle 34. The pin 39 is operated by a bell ended lever 43 secured to the metering control shaft 20 which in turn is actuated by either the power cam 16 on the cross-shaft 15 or a throttle cam 44 on the throttle shaft 25.

The cross-shaft 15 carrying the power cam 16 is actuated by a ball ended lever 45 slideable in a horizontal guide passage 46 in the air valve 14, so that an opening movement of the air valve 70 causes counter-clockwise rotation of the cross-

shaft 15 in Figures 4 and 8. The power cam 16 cooperates with a short armed lever 47 on one end of the metering control shaft 20, adjustment being provided by means of a set screw 48. Similarly, the throttle cam 44 cooperates by means of a rod 49 with a long armed lever 50 on the control shaft 20, another set screw 48 providing for adjustment between the lever 50 and the rod 49.

The cams 16 and 44 are somewhat similar in 10 construction in that an adjustable spring face 51 is utilized, the center portion of which is in contact with a central peak 52 on the cam, and each end of the spring is adapted to be individually raised or lowered relative to the cam by set 15 screws 53. If necessary for accurate calibration, the spring faces 51 can be preformed to assume other than its natural curve when bent over the cam peak.

The power cam 16 limits the rise of the short lever 47 and thereby limits the opening movement of the metering pin. The opening of the metering pin in relation to the opening of the air valve is thus controlled by the contour of the power cam throughout the power range. It is thus possible to provide varying fuel ratios for varying conditions over the entire speed range of an engine, as by varying the lower end 54 of the cam for adequate pick up, and the upper end 55 for high speed operation, without affecting the central portion of the range, which latter is adjusted by means of the screw 48 in the short lever 47 which modifies the whole range.

The throttle cam 44 provides a driving range mixture control which provides a normally leaner mixture ratio than the power cam 16, so that the cam 44, acting through the push rod 49 on the long lever 50, normally holds the short lever 47 out of contact or away from the power cam 16. The throttle cam 44 has its spring face 51 calibrated for best economy on a given engine and car load for constant speeds on a level road. A screw 56 on the end 57 of the cam nearest the push rod 49, when the throttle is closed for idling, serves to provide the idling adjustment, which is 45 made directly on the fuel through the metering pin 39, and blends smoothly into the higher speeds as the throttle is opened without a transition point or "spot", as when a conventional 50 idling bypass is used. The adjusting screw 48 in the long lever 50 varies the mixture over the whole partial throttle opening range, while the idling adjustment screw 56 affects only the lowest or idling speeds.

The throttle position determines the metering 55 pin location under normal conditions at any partial throttle opening, the air valve being free to open or close according to the air passing through it. If the car and engine are operating at the speed called for by the throttle position, then the 60 throttle cam 44 controls the metering pin and holds the short lever 47 away from the power cam 16, so that the mixture calibration corresponds to the best economy. On an up-grade, during acceleration, or while warming up a cold engine, 65 the engine will run slower at a given throttle opening so that the air valve will not open as far, and the mixture will be correspondingly richer. If, however, the engine load is lighter and the engine runs faster, as on a down-grade, 70 or when the throttle is closed for deceleration, the air valve will open farther than the throttle position would demand normally and the mixture will be leaner. This lean mixture, characteristic when the engine temporarily speeds up, tends to 75

burn out carbon, and does no harm to the engine because it does not occur under load and is of short duration.

When the throttle is opened for acceleration, 5 the power cam 16 comes into play as the throttle cam 44 rotates far enough to drop the push rod 49 out of contact with the long lever 50, allowing the power cam to control the metering pin 39 through contact with the short lever 47, so that 10 coincident with the throttle opening the mixture is enriched to that calibration chosen for best power at the given speed as determined by the air valve opening and the contour of the power cam 16.

15 If the throttle is opened slowly enough so that the air valve 14 does not jump, no extra acceleration fuel is required, as a gradual opening of the air valve supplies more fuel in step therewith, the ratio being determined by the power cam 20 profile and the profile of the air valve and its profiled passage, the two profiles being preferably so laid out that the air valve travel will be proportional to the increasing volume of air admitted past the valve in order to simplify the requirements of the profile of the cam 16.

The cross-shaft 15 carries a lever 53 which operates a rod 59 carrying a piston 60 loosely fitting in the accelerating pump and dash pot chamber 28, the arrangement being such that 30 a slow opening movement of the air valve will move the piston downwardly in the chamber 28 at a speed slow enough to allow the fuel therein to bypass around the piston. On the other hand, a rapid downward movement of the 35 piston will apply pressure on the fuel therebelow, since the ball check 36 will close the fuel passage 35. Accelerating fuel is taken from the chamber 28 through a port 61 in the wall considerably above the bottom of the piston stroke, 40 this port leading to a valve seat 62 controlled by a weighted valve 63 which lifts in response to fuel pressure to allow fuel to be discharged through a passage leading to an accelerating jet 65. The valve 63 is ported at 64 to communicate with the air above the fuel in the fuel 45 chamber to kill any suction tending to lift the valve 63. The travel of the valve 63 is limited by the cover 49 after it has been forced open far enough to shut off the air ports 66 to prevent fuel from being discharged therethrough. 50 Preferably, the valve 63 is a loose fit in its guide so that some of the fuel escapes around the sides of the valve, as such an arrangement permits the use of a larger drill in the accelerator jet 55 65 which is proportioned to the acceleration requirements of the engine on which the carburetor is to be used.

If the throttle is opened suddenly, the air valve moves rapidly and the clearance around 60 the piston 60 is insufficient to allow fuel to escape, causing delivery of accelerating fuel until the piston 60 covers the port 61. Thereafter, the piston serves only as a steady dash pot which enriches the mixture by retarding the 65 opening of the air valve. The check valve 36 allows a free return of the piston and air valve. Preferably the port 61 is so located that it is cut off at about one-third of the piston's travel, corresponding to about 30 M. P. H. in the vehicle, but the exact location may be varied for 70 different engines. Variations in acceleration fuel requirements may also be made by varying the piston clearance, the size of the accelerator jet 65 and the clearance about the valve 63.

75 Provision for starting and warming up is made

by means of a choke control which acts to progressively add increasing spring tension opposing the opening of the air valve and to retract the metering pin 39 to also increase the fuel flow. This is accomplished by means of a choke 5 lever 66 adjustably mounted on a U-shaped bracket member 67 which is pivoted on a stub shaft 68 between the cross shaft 15 and the metering control shaft 20 as this mechanism acts on both shafts.

An initial slight movement of the choke lever 66 brings the U-shaped bracket member 67 into contact with one end 69 of a torsion spring 70 on the cross-shaft 15, the other end 71 of the spring engaging the accelerator lever 53 so that 15 continued clockwise movement of the bracket member 67 in Figure 7 imposes additional spring load on the air valve 14. Simultaneously, a lug 72 on the bracket member 67 moves to contact a stop 73 carried by the metering shaft 20 in 20 a direction to rotate the shaft and increase the opening of the metering pin 39. The bracket and spring strength is such that the spring will hold against cranking speed engine suction, but will allow the air valve to open when the engine 25 starts, and if the motor is raced with the choke on, the added force acting on the air valve tends to kick off the choke, thus releasing the same and returning the carburetor to normal operating conditions.

30 Since the cams 16 and 44 act on the long and short levers 50 and 47 to restrain opening movement of the metering pin 39, it is necessary, to provide the foregoing choke operation, that the shaft 20 be movable relative to the levers. To 35 this end, the two levers are mounted on a sleeve 74 rotatable on the shaft 20, and a torsion spring 75 normally holds the long lever 50 against a stop 76 secured to the shaft 20. Under normal operating conditions, the levers 47 and 50 may 40 be considered rigid with the shaft 20, but when the choke control is actuated the shaft 20 can rotate clockwise, in Figure 3, beyond the limiting position of the levers as determined by the cams 16 and 44.

45 For further efficiency in starting, a small aperture 77 in the center of the air valve 14 communicates through the tubular extension of the fuel nozzle with the nozzle 34 proper. This air passage is small, and at starting speeds the 50 suction in the carburetor produces a high air velocity which effects a good atomization of the fuel entering the nozzle, thus helping starting and minimizing crankcase dilution.

The profile of the air passage 13 is very important, as air velocities controlled by the relative contours of the air valve and passage walls are worked out to permit the use of lighter air valve springs and to obtain air valve travel and power cam movement proportional to the volume of air flow. This air valve spring is worked out so light that if the air valve is opened by engine suction without a corresponding increase in the metering pin opening, a leaner mixture results. This gives the carburetor its unique 60 automatic mixture changing characteristics with partial throttle openings. At higher engine speeds, the lower side of the air valve rides on a very high velocity air stream and is thus prevented from snapping wide open because of the 65 use of a slight spring.

70 It will thus be seen that I have invented an improved air valve type of carburetor wherein the faults common to previous air valve carburetors have been eliminated by the use of an 75

air valve arranged to move in proportion to the volume of air flowing therewith and opposed by a relatively light spring which provides a characteristic tending to lean the mixture as the 5 valve opens, in combination with a power cam operated by air valve movement to controllably increase the fuel flow, whereby when the engine operates at a higher speed than normal for a given throttle opening, as when the engine is 10 lightly loaded, the mixture will be leaned out, while when the engine is operating slower than normal, as when pulling hard for a given throttle opening, such as occurs during warm-up, acceleration and hill-climbing, the mixture will 15 be automatically enriched to a varying power mixture determined by an adjustable cam operated by the air valve. The carburetor of this invention thus provides an automatically adjustable mixture control providing maximum 20 economy for normal operation and the maximum power obtainable from an enriched mixture when operating conditions so require.

I am aware that many changes may be made and numerous details of construction may be 25 varied through a wide range without departing from the principles of this invention, and I, therefore, do not purpose limiting the patent granted hereon otherwise than is necessitated by the prior art.

30 I claim:

1. In a carburetor of the air valve type, an air valve, spring means urging said air valve to closed position, a fuel supply reservoir, a nozzle in communication with said reservoir, fuel metering means including a fuel valve, spring means urging said fuel valve to open position, a first cam connected with said air valve and oscillable by movement of said air valve, a first cam follower operably connected with said fuel valve, a throttle, means including a second cam and 40 a second cam follower operably connected with

said throttle and linked with said fuel valve, both of said cam followers being arranged to limit opening movement of said fuel valve, said second cam and said second follower being so constructed and arranged as to permit opening 5 of said fuel valve upon part opening of said throttle until prevented by engagement of said first-mentioned cam with said first follower, further opening of said throttle beyond a predetermined part opening being effective to disengage 10 said second cam and said second follower from control of said fuel valve and to put said air valve in complete control of said fuel valve.

2. In a carburetor of the air valve type, spring means urging said air valve to closed position, 15 a fuel supply reservoir, a nozzle in communication with said reservoir, fuel metering means including a fuel valve, spring means urging said valve to open position, a follower operably connected with said fuel valve, a throttle, a first 20 means solely effective to adjustably limit opening movement of said fuel valve while said throttle has been turned to an open position beyond a predetermined part opening, a second means solely effective to adjustably limit opening movement of said fuel valve while said throttle is being turned through a range of from closed position to a position of predetermined part opening, said first means comprising a movable cam member connected movable with said 30 air valve and engageable by said follower, and said second means comprising a movable member connected movable with said throttle and engageable with said follower, said second means being arranged to move said follower out of 35 engagement with said cam member and to adjustably limit opening of said fuel valve while said throttle is being turned from a predetermined position of partial opening to closed position.

40
GEORGE A. BREEZE.
